UNITED STATES PATENT OFFICE

136,946

DESIGN FOR A MEASURING RULER OR SIMILAR ARTICLE

Herbert Austin Aikins, Cleveland Heights, Ohio

Application October 11, 1943, Serial No. 111,331

Term of patent 14 years

To all whom it may concern:

Be it known that I, Herbert Austin Aikins, a citizen of the United States and a resident of Cleveland Heights, county of Cuyahoga, and State of Ohio, have invented a new, original, and ornamental Design for a Measuring Ruler or Similar Article, of which the following is a specification, reference being had to the accompanying drawing, forming a part thereof.

In the drawing—

Fig. 1 is a plan view of a measuring ruler showing my new design, the article being of conventional thickness;

Figs. 2 and 3 are enlarged fragmentary detail views of sections of the ruler; and

Fig. 4 is a further enlarged fragmentary detail view of the portion IV of Fig. 3.

The dominant feature of the design, as shown in full lines, consists of a fanciful "measuring worm" covering the scope of the individual unit, such as an inch, and with the intermediate markers and spacers in uniform widths.

What I claim is:

The ornamental design for a ruler or similar article, substantially as shown and described.

HERBERT AUSTIN AIKINS.
